UNITED STATES PATENT OFFICE.

CLARENCE A. DIX, OF DETROIT, MICHIGAN.

METAL-SHAPING MACHINE.

Application filed May 5, 1926. Serial No. 106,919.

This invention relates to metal re-working machinery.

This invention has utility when incorporated in apparatus for seaming, beading, or 5 wiring in, an edge or edges of sheet material.

Referring to the drawings:

Fig. 1 is a side elevation, with parts broken away, of an embodiment of the invention as a wiring-in machine;

Fig. 2 is a fragmentary front view of the machine of Fig. 1;

Fig. 3 is a view, in section, of the clutch connection for the machine showing the belt drive for the clutch instead of the gear operation as shown in Fig. 1;

Fig. 4 is a section on the line IV—IV, Fig. 3;

Fig. 5 is a view of the first roll pair drive 20 and the adjustable mounting for the upper roll of said pair in the head of the machine in a view from the right of Fig. 2 with the plate removed and other portions broken away;

Fig. 6 is a detail view of the lock toggle device of Fig. 5 for the upper roll adjustment showing the toggle in collapsed position;

Fig. 7 is a section on the line VII—VII, Fig. 5;

Fig. 8 is a plan view of the head of the machine of Fig. 1, parts being broken away;

Fig. 9 is a detail view of the handle set for the upper roll of the first pair, being 35 partially on the line IX—IX, Fig. 1;

Fig. 10 is a view of the head from the left of Fig. 2, portions being broken away;

Fig. 11 is a fragmentary plan view of the head of Fig. 8 with the working pairs angularly adjusted instead of being in the straight line as shown in Fig. 8;

Fig. 12 shows the assembly relation for the sheet material and the wire as adjacent the edge thereof as supplied to the first 45 working pair in the device of this disclosure;

Fig. 13 shows the position of the stock as being handled after being acted upon by the first working pair with the sheet edge turned to L-position;

Fig. 14 shows the stock as passing the second working pair with the sheet material given its bend back or U-form in shape for seaming, if the wire were not used;

Fig. 15 shows the condition of the work 55 as acted upon by the third pair in closing

in the edge of the sheet material as turned in to form a bead for the sheet material;

Fig. 16 is a view from the left of the assembled in which the third roll pair is not assembled, showing the second working pair; 60

Fig. 17 is a fragmentary plan view of the working pair of Fig. 16;

Fig. 18 is a front view of the working pair of Fig. 16 associated with the first working pair of rolls; and Fig. 19 is a detail of the convex spiral tooth feature of the gears.

Base 1 is shown as having thereon column 2 and bracket 3. Pedal 4 is pivotally mounted in the bracket 3 and has arm 5 (Fig. 1) extending for connection with upwardly extending link 6 to arm 7 having fixed bearing 8 in bracket 9 as carried near the upper portion of the column 2. This column 2, near its lower portion, has auxiliary 70 bracket 10 mounting prime mover, as motor 11, having shaft 12 carrying pinion 13 in mesh with gear 14 mounted on stud 15 carried by the column 2. Fixed with the gear 14 in this speed reduction transmission train, 75 is pinion 16 in mesh with teeth 17 on wheel 18.

In the instance when it is not desired to have individual motor drive, the wheel 18 may have belt face 19 for belt drive (Figs. 85 3, 4) operation. This wheel 18 is provided with anti-friction bearings 20 loosely mounting wheel 18 on hollow shaft 21 mounted by the column 2. This wheel 18 is provided with clutch face 22 into engagement with 90 which may be thrown clutch member 23 also loosely mounted on the shaft 21. This clutch member 23 carries a pair of pins 24 which are reciprocable in openings of spider 25 fast with tubular shaft 21. On the opposite side from this clutch 22, 23, as to the wheel 18, this tubular shaft 21 carries pinion 26 fast therewith. As the pedal 4 is depressed, the upwardly extending link 6 is drawn downwardly so that upper balancing 100 spring 27 (Fig. 1), as adjusted by collar 28, is compressed toward bracket 29 carried by the column 2, while lower balancing spring 30, as adjusted by collar 31, on the link 6 is released. This movement of the link 6

downward pulls the arm 7 downward on its bearing 8 to rock arm 32 away from the column 2. Arm 32 is provided with angular extension 32' positioned as to arm 7 by adjusting screws 32''. This serves to 105 110

take up wear in clutch members 22, 23, and insures the working in unison of clutch members 22, 23, and toggle members 76, 77. This arm 32 is engaged between collars 33, 34, on stem 35 through the column 2 and the tubular shaft 21. Accordingly, this swinging of the arm 32 away from the column 2, pulls the stem 35 axially of the tubular shaft 21 so that transverse pin 36 carried by the stem 35 is operable in slot 37 of the tubular shaft 21, and in this operation engages the member 23, to draw such member 23 as loosely mounted on the tubular shaft 21, axially of this shaft 21 to bring the clutch face 23 into driving engagement with the clutch face 22. Accordingly, there is driving transmission from the motor 11 or from the driving belt on the pulley face 19 which, as actuating the wheel 18, serves to rotate the pinion 26 effective through an offset transmission, herein shown as gear wheel 38 on trunnion 39 carried by the column 2 for rotation of pinion 40 on shaft 41 mounted in bearings 42, 43, as the machine head on the column 2. This bearing unit member 42, 43, has extension 44 in which is removably mounted a work supporting table 45 (Figs. 1, 3, 5).

In instances wherein it is desired to rotate the shaft 41 (Fig. 1) slightly, as for adjusting position of the gearing, or other purposes, or even for doing a slight amount of work other than by power drive, crank 46 may be mounted on keyed end 47 of this shaft 41. This shaft 41, adjacent the table 45, is provided with rotatable reforming roll 48 herein shown as effecting the first flanging or upsetting operation. Adjacent this working roll 48 and mounted coaxially with this shaft 41, is gear 49 herein shown as spiral with teeth convex, the convexity being from a radius 50, less than the radius of the gear 49. This shaft 41, between the bearings 42, 43, has thereon pinion 51 in mesh with gear 52 on shaft 53 approximately axially parallel with the shaft 41. This shaft 53 is carried by unitary member 54 providing bearings 55, 56, upon opposite sides of this pinion 52 for this shaft 53 (Fig. 5). Take-up washers 53' co-operate with lock nuts 53" in holding the shaft 53 from longitudinal play. This shaft 53 in opposing working relation as to the working roll 48 carries companion working roll 57, as the upper roll of this initial terminal roll pair of sheet material edge re-working members.

The unitary member 54, has upwardly of the pinion 52, recess 58, in which is mounted block 59 through which extends pivot bolt 60 in providing a pivot bearing for this member 54 in the head of this machine comprising upwardly extending portion 61 from the bearings 42, 43, and laterally thereof a plate 62, as an opposite closure member for housing this member 54. This plate 62 is

mounted on the machine head member 61 by bolts 63 and dowels 63'. The member may be adjusted as to its axis block 59 by slackening off set screw 64 and drawing up bolt 65 with setting of the nuts 66 thereon for positioning wedge face 67 of this bolt 65 against the block 59 for thus shifting member 54 on the axis 60 further away from the working roll 57. Converse operation of these adjustments will shift the roll 57 toward the roll 48. These adjustments 64, 65, 66, may be locked for holding the parts in the set position.

Way 68 has coil spring 69 therein operating against plunger 70, abutting stop 71 fixed with the head 61 so that there is (Fig. 5) an independent action in the throw down of the roll 57 toward the roll 48, as well as a normal tendency to hold such rolls adjacent and take up any lost motion in the adjustment of such rolls toward each other. The actual throwing of this first roll pair 48, 57, into and out of operative position is effected by rocking shaft 72 which carries arm 73 from which extends link 74 to pin 75 having pivotal connection with lower thrust member 76 and upper thrust member 77 of a toggle pair. This lower member 76 is rockable in seat 78 of the member 54 adjacent the bearing 56. The upper toggle member 77 is rockable in bearing 79 of block 80 shiftable in guide 81 by wedge 82 as adjustable by threaded device 83 having head 84 coacting with fork extension 85 from the head 61 of the machine. This wedge adjustment determines the throw position of the roll 57 toward the roll 48, and as so thrown the toggle members 76, 77, are just beyond aligned position to set or self-lock as a toggle with abutting faces 86 affording stop 105 coaction therefor. The adjustment of the wedge 82 determines to a nicety, the clearance, while the buffer spring 69 takes up any lost motion and holds this toggle assembly in snug coacting relation.

The frame member 61 is provided with bearing extension 87 (Fig. 1) for hinge pin 88 (Fig. 8). This hinge pin 88 has its axis approximate the axis of the radius 50 of the gear 49, with hinge pin 88 extending laterally of and transversely of the general extent of the axes of the shafts 41, 53, as approximately parallel and disposed in a vertical plane. This means that frame 89 carried by hinge pin 88 has its axis such that there may be a very close, or short radius of turning as to the first working pair, and makes possible in the turning out of work in the operation of this machine on a radius closely approximating that of the radius of the roller 57. This frame 89 carries shoe 90 (Fig. 10) for holding the wire against shifting out of position and at the angle as provided in the work. Additionally, this frame 89 carries (Fig. 2) roll 91

for effecting the return bend or folding back operation on the sheet material. This roll 91 is driven by cylindrical faced spirally toothed gear 92 in mesh with the gear 49. The teeth of the gear 49 have extent transversely of such gear 49 convex face. However, to take care of the shorter radius of the termini of this convex face of this spiral gear 49, the projection portion of the teeth is narrowed toward the termini, while the space or recess portion is maintained constant throughout the transverse extent. This really strengthens the thinner tooth portions, as the ends of the teeth terminate in most effective shrouds, which would not be in evidence were the teeth to extend straight across the face.

The gear 92 is mounted on shaft 93 in this member 89 carrying the second working pair. This shaft upwardly extends to carry cylindrically faced spiral gear 94 in mesh with convex faced spiral gear 95, similar to the convex faced gear 49. This gear 95 (Fig. 10) is loosely mounted on trunnion 96 carried by frame 97 having connection by hinge pin 98 with the frame 89. This gear 95 is in mesh with cylindrical faced spiral gear 99 fast with lower third working pair comprising roller 100, as the lower roll of such pair, opposed by upper roller 101 rotatably mounted on extension 102 eccentric of the trunnion 96. This final or follower, as the terminal working pair of these rolls, comprising the rolls 100, 101, effects the final reverse bending or bead forming for enclosing the wire in finishing the edge of the sheet material.

Fast with the trunnion 96 is a gear 103 in mesh with segment 104 having fixed fulcrum 105 in the frame 97. Handle 106 upwardly extends from this fulcrum 105 and is fixed with the segment 104. This handle 106 has a plunger 107 therein (Figs. 2, 10) which is depressed to release ratchet 108 from fixed quadrant 108' against the action of spring 109. With the handle 106 thus free for rocking, this trunnion 96 is rotated on an axis eccentric of the stud 102 so that the position of the upper roll 101 of this follower 50 roll pair may be changed as to the lower live roll 100 of this pair. At the determined working position for the handle 106, cam 106' is thrown thereagainst and backed by nut 106'', thus restricting the range of throw for the handle 106. This may be an adjustment for working operation to have the throw out operation independently of effecting the transmission connection or driving of the roll 100 for this rocking of the trunnion 96 does not disturb the mesh relation of the gear 95 with its driver 94 and the driving member 99. The angular relation of this third working pair as to the second pair may be angularly shifted on as close or short a radius as that available be-

tween the first and second working pair. The wire may act as a pilot.

Accordingly, the relative angular shifting of these three working pairs are adjusted automatically to the character of work which it is desired to turn out by the edge configuration of the work effective to hold the succeeding work in pairs as desired.

The shoe 90 of the second working pair is mounted with the frame 89 by the stem 112 having crank 113 provided with handle 114 so that this shoe 90 may be swung away from the work to allow the wire to come into position and then swing back to hold the wire into position at the return bend operation as effected at the second working pair. The throw of this crank 113 is limited by stop 113'.

In placing the work initially at the first working pair, such may be clamped in automatically with the depression of the pedal 4. To this end, upwardly extending from the arm 7 is link 115 (Fig. 1). This link 115 is provided with spring 115', the tension of which is governed by screw 116. The object of this spring 115' is that should any piece of stock be inserted in the machine, which was too heavy in gage, or too hard in temper for the machine to work in safety, the spring will give, and thus toggles 76, 77, will not operate, and rolls 48, 57, will not be brought together. This link 115 extends to short arm 117 fulcrumed on bolt 118 in plate 62. This arm 117 has fixed therewith long arm 119 of this lever loosely connected to arm 120 of plate 121 loosely mounted on shaft 72. This plate 121 has recess 122 engaged by pin 123 as normally thrust therein by spring 124 (Figs. 1, 8). This pin 123 is in collar 125 having key connection 126 with this shaft 72. There is in the depression of the pedal 4, such a rocking of the shaft 72 as swings the arm 73 (Fig. 5) to throw the toggle 76, 77, into position for its faces 86 to abut and thereby automatically lock the roll 57 into the clearance as determined by the wedge 82 as to the opposing roll 48 of the first working pair.

Accordingly, in this mode of operation, the rolls 48, 57, at once begin to rotate for feeding the work through the machine as these rolls approach each other in clamping position as to the work. However, if it be desired to position the work before starting the machine, this is done by the machine attendant operating handle 127. This handle 127 (Figs. 1, 8, 9) is provided with cam faces 128, 129, extending from recess 130, which recess 130 in normal position of the handle 127 is in registry with the recess 122 of the plate 121, thus allowing the pin 123 to have key connection with the plate 121. However, in this oscillation of the handle 127 relatively to the plate 121, this cam face 130

128, in one direction, and this cam face 129, in the opposite direction, engage shoulder 131 on the pin 123 and thus operate such pin 123 against the resistance of spring 124 to withdraw such pin 123 from the opening 122. Thereafter, further operation of the handle 127 effects rocking of the collar 125 and thus rocks the shaft 72 for throwing the toggle pair 76, 77, into or out of the roll holding position.

In operating the machine hereunder, a sheet of stock, as sheet metal 132, may be placed to have its edge 133 in position toward the gear 49 over the working roller 48. Wire 134 may be placed in position under the working roller 57 approximating the clearance of the inner side of the working roll 57, as a plane. This work may be placed in position and the clamping occur by the operation of the handle 127 to bring the roll 57 down into position to direct the wire against the flange of the roll 48. As so operated the depression of the pedal 4 connects the continuously operating motor 11 for a transmission drive in rotating the shafts 41, 53, and thus rotating the rolls 48, 57. In the event the operator does not initially place the stock between the inactive rolls 48, 57, for clamping, the positioning of the work at the operation of the pedal 4 may not only effect the driving of the rolls 48, 57, but the simultaneous swinging of the roll 57 into the working position toward the roll 48 through the action of the link 115 and the lever 117, 118. The work as passing this first live roll working pair is delivered to the second working pair. The shoe 90 may be rocked to hold the wire 134 into position as the roll 91 is effective for changing the upstanding or L-portion 135 to a return bend portion 136 (Figs. 13, 14). Further progress of this stock is to the third working pair, herein a vertical roll pair comprising the live lower roll 100 and the follower upper roll 101 wherein final bead bend 137 (Fig. 15) is effected about the wire 134.

It is to be noted in this machine, that the driving connections are to the lower rolls of the rotary working pairs, or that the entire transmission is accordingly below the plane of the sheet stock as being operated upon, which means in any non-straight line shapes, there is ample clearance about the head of the machine for the excess stock even extending from the edge being finished. The short radius and convex face of the transmission gears permits short range of adjustment between the pairs so that short arc curvatures may be worked effectively on the stock. The work may be clamped or released at any working pair independently of effecting the transmission at the second and third pair and independently of transmission starting at the first pair. Besides this adjustment in the plane of the rolls to various

curvatures or arcs, there is vertical arc adjustment by shims or washers 138 placed about or removed from the hinge pins 88, 98. It is as important that the swinging members 89, 97, may have vertical adjustment 70 downwardly, from the plane of working face of roll 48 as well as adjustment upwardly, and the removal of the washers, or shims, 138, allows swinging members 89, 97, to float with the work, up or down. These 75 members 89, 97, are accordingly provided with means for universally locating the adjustment of these members.

In instances where the edge finish is to be merely a return bend as for seaming, the 80 final roll pair may be left off and such structure is shown in Figs. 16, 17, 18. Herein the shoe 90 instead of being swung outward on an axis, from within the frame 89 may be directly reciprocated in and out. To 85 this end, the frame 89 has its stem 112 provided with eccentric pin 139 engaging angle portion 140 from the shoe 90 so that crank 141 is provided with rocking handle 142, when such handle is raised out of locking 90 relation with toothed segment 143 such handle may then be swung outwardly and thus directly shift the shoe 90 out of working position.

What is claimed and it is desired to secure 95 by United States Letters Patent is:—

1. A forming machine for an edge of sheet material comprising a plurality of vertical pairs of forming members, a member of each pair having a sheet material directing flange portion, said flange portions being in sequence for folding the sheet material back on itself, and rotatable driving means for the lower members of a plurality of said pairs. 100

2. A forming machine for an edge of sheet material comprising a plurality of vertical pairs of forming members, a member of each pair having a sheet material directing flange portion, said flange portions being in sequence for folding the sheet material back 105 on itself, the upper rotatable members of said pairs being follower members actuated from the lower members of said pairs, and rotatable driving means independent of the material acted upon for a plurality of said lower members. 110

3. A forming machine for an edge of sheet material, comprising three pairs of forming members having stop means fixed therewith at approximately aligned position of the toggle, a rotatable member in each pair, and driving means independent of the material 115 acted upon for each of said rotatable members.

4. A forming machine for an edge of sheet 120 material comprising a pair of rolls forming therebetween a way for bending the sheet material as to an edge thereof, and means for adjusting one of said rolls relatively to the other comprising a toggle having stop means 125

fixed therewith at approximately aligned position of the toggle.

5. A forming machine for an edge of sheet material comprising a pair of rolls, a fixed 5 mounting for one of said rolls, a shaft for the other thereof, an actuating gear on said shaft, a one-piece bearing-providing member for the shaft extending to both sides of said gear, actuating means for said gear, and 10 means for adjusting said bearing for shifting its shaft and roll into and out of operative position as to the other roll.

6. A forming machine for an edge of sheet 15 material comprising a pair of rolls, a fixed mounting for one of said rolls, a shaft for the other thereof, an actuating gear on said shaft, a one piece bearing providing member for the shaft extending to both sides of said gear, actuating means for said gear, a 20 pivot mounting for said bearing, and means for swinging said bearing and its shaft and roll on said pivot mounting for shifting its shaft and roll into and out of operative position as to the other roll.

25 7. A forming machine for an edge of sheet material comprising a pair of rolls, and means effective during rotation of the rolls for adjusting one of the rolls axially as to the other.

30 8. A forming machine for an edge of sheet material comprising a roll pair, a pedal for shifting one roll relatively to the other, and a mounting for holding said other roll against shifting during the relative shifting 35 of the one roll.

9. A forming machine for an edge of sheet 40 material comprising a roll pair, one of which rolls is shiftable as to the other, a drive for the rolls, and a manually operable controller for said drive effective for shifting 45 said shiftable roll.

10. A forming machine for an edge of sheet 45 material comprising a plurality of pairs of members, a rotatable member in each pair, and spiral gear transmission from one pair to another pair.

50 11. A forming machine for an edge of sheet material comprising a plurality of pairs of members, a rotatable member in each pair, mounting means permitting relative 55 rocking of the rotatable members to vary the angular relation between their axes, and driving means independent of the material acted upon for rotating members in different pairs.

12. A forming machine for the edge of sheet material comprising a first pair of rotary metal working elements, a second pair of elements, one of which is rotatable, an 60 angularly adjustable connection between said pairs having its axis lateral of the axis of said rotary pair of elements, and transmission connection between said pairs of elements including toothed members.

65 13. A forming machine for the edge of

sheet material comprising a first pair of rotary metal working elements, a second pair of elements, one of which is rotatable, an angularly adjustable connection between said pairs having its axis lateral of the axis of 70 said rotary pair of elements, and transmission connection between said pairs of elements including toothed members, one of which has its face as meshing with the other on a radius from the axis of said connection. 75

14. A forming machine for the edge of sheet material comprising a plurality of vertical pairs of working elements including terminal pairs thereof, said terminal pairs being rolls, rotatable driving means independent of the material acted upon from one terminal pair to the other for the lower rolls, and a transmission about an upper roll for the follower lower roll.

15. A forming machine for the edge of sheet 85 material comprising a plurality of vertical pairs of working elements including terminal pairs thereof, said terminal pairs being rolls, and rotatable driving means from one terminal pair to the other for the 90 lower rolls, comprising a transmission for rotating a roll including a gear about an axis of one of said rolls and eccentric thereto.

16. A forming machine for the edge of sheet material comprising a plurality of 95 pairs of members including terminal pairs thereof, said terminal pairs being roll pairs, an adjustable mounting for one terminal pair of rolls as to the other terminal pair of rolls, and additional means for shifting 100 said adjustably mounted terminal roll pair from working position independent of effecting the rotation and independent of distributing the cooperative relation of the other terminal roll pair.

17. A forming machine for the edge of sheet material comprising rotary forming 105 rolls and a drive therefor including a wheel, a hollow shaft therefor, an actuator, and control means through said shaft for connecting 110 the wheel to said shaft.

18. A forming machine for the edge of sheet material comprising rotary forming rolls and a drive therefrom including a 115 wheel, a hollow shaft therefor, an actuator, and adjustable control means through said shaft for connecting the wheel to said shaft.

19. A forming machine for the edge of sheet material comprising a first pair of co-acting complementary rotary forming rolls, 120 a second pair of coacting complementary members, a vertically adjustable mounting for the second pair as to the first pair, and means for rocking said mounting for varying the working position of said second pair of members as to the first pair of rolls.

20. A forming machine for the edge of sheet material comprising a first pair of rotary forming rolls, a second pair of members adjustable to provide a drop from said 130

first pair including a shoe, and means for positioning said shoe.

21. A forming machine for the edge of sheet material comprising a plurality of pairs of members including terminal pairs thereof, said terminal pairs being roll pairs, and means for adjusting the upper rolls of said pairs upwardly away from the lower rolls, whereby the material as acted upon may be supported independently of shifting during said adjusting of the upper rolls.

22. A forming machine for the edge of sheet material comprising a plurality of pairs of members including terminal pairs thereof, said terminal pairs being roll pairs, and means for adjusting the upper roll of the follower terminal pair upwardly away from its lower roll, whereby the material as acted upon may be supported independently of shifting during said adjusting of the upper roll.

23. A forming machine for the edge of sheet material comprising a lower forming roll, an upper forming roll, means for rotating both rolls, and an adjustable mounting permitting upward shifting of the upper roll away from the lower roll, whereby the material as acted upon may be supported independently of shifting during said adjusting of the upper roll.

24. A forming machine for the edge of sheet material comprising a lower forming roll, an upper forming roll as a first pair, a second forming pair of members thereafter and a mounting for the second pair adjustable for the working position below the first pair.

25. A forming machine for the edge of sheet material comprising a plurality of working pairs of members, and adjustable spacing means for one member as to its companion pair member embodying a rock arm and means adjustable for limiting the shifting of said arm.

26. A forming machine for an edge of sheet material comprising forming members

including relatively angularly adjustable rolls determining a working path for the progress of the material along therebetween, and driving mechanism for a plurality of said rolls below said working path.

27. A forming machine for an edge of sheet material comprising a first pair of forming members, a mounting therefor, a second pair of forming members, a hinge pin mounting for the second pair of forming members swingable as to the mounting for the first pair of forming members, and shims on said pin.

28. A forming machine for an edge of sheet material comprising a plurality of pairs of forming members, mounting means for the members including a mounting for the final pair of said forming members embodying a hinge pin, and shims coacting with said pin.

29. A forming machine for the edge of sheet material comprising a lower forming roll, an upper forming roll as a first pair, a second forming pair of members thereafter, and a loose mounting for the second pair including means universally adjustable for locating the working position of the second pair as to the first pair.

30. A forming machine for the edge of sheet material comprising a lower forming roll, an upper forming roll as a first pair, a second forming pair of members thereafter, and a vertically loose mounting for the second pair including means horizontally swingable and vertically adjustable for locating the working position of the second pair as to the first pair.

31. A forming machine for the edge of sheet material comprising, in series, a plurality of pairs of working elements, said series terminating in terminal roll pairs of said elements, and rotatable driving means from one terminal pair to the other.

In witness whereof I affix my signature.

CLARENCE A. DIX.

CERTIFICATE OF CORRECTION.

Patent No. 1,719,002.

Granted July 2, 1929, to

CLARENCE A. DIX.

It is hereby certified that error appears in the printed specification of the above numbered patent requiring correction as follows: Page 4, line 103, claim 1, after the word "means" insert the words "independently of the material acted upon"; same page, claim 3, line 119, beginning with the word "having" strike out all to and including the word "toggle" line 121, and insert instead ", a member of each pair having a sheet material directing flange portion, said flange portions being in sequence for folding the sheet material back on itself"; and that the said Letters Patent should be read with these corrections therein that the same may conform to the record of the case in the Patent Office.

Signed and sealed this 13th day of August, A. D. 1929.

M. J. Moore,
Acting Commissioner of Patents.
